UNITED STATES PATENT OFFICE.

WALTER HANSELL, OF BROOKLYN, NEW YORK.

MUSICAL INSTRUMENT.

Application filed May 25, 1926. Serial No. 111,607.

The present invention is concerned with the provision of a musical instrument and finds its preferred embodiment in a wind instrument of the all-metal type, in which 5 a series of closed tubes are used, and in which vibrating reeds or similar devices are eliminated.

Preferably the instrument of the present invention is provided with a mouthpiece 10 generally similar to the mouthpiece of a harmonica, and is played in the same manner as a harmonica by inhaling and exhaling through the mouthpiece. The device may have either the same number of notes as a 15 harmonica, or may cover any other range of notes.

An object of the invention is to provide a device of this character which may be played by anyone familiar with the method of playing a harmonica, and yet which will give a 20 much sweeter, clearer tone.

Another object of the invention is to provide a musical instrument of the general character noted above, of simple, practical 25 construction, which is extremely unlikely to get out of order, which may be conveniently handled, and which will combine the simplicity of operation of the harmonica with the clear sweet tones of a metal instrument. 30

A further object of the invention is to provide a musical instrument which may be manufactured with comparative economy, and which may be readily disassembled for 35 purposes of cleaning or repair.

With the above noted and other objects in view, the invention consists in certain novel features of construction and combinations and arrangements of parts, as will be 40 more fully hereinafter set forth and pointed out in the claims. The invention may be more fully understood from the following description in connection with the accompanying drawings, wherein—

Fig. 1 is a top plan view of an instrument embodying the present invention.

Fig. 2 is a view partly in side elevation and partly in vertical section through the instrument on the staggered line 2—2 of 50 Fig. 1.

Fig. 3 is a vertical sectional detail on the line 3—3 of Fig. 1.

Figs. 4 and 5 are fragmentary perspective views of two of the tube sections.

In the drawings I have used the reference character 10 to designate an elongated

mouthpiece which may be in the nature of a metal bar, or may be of other suitable material. A series of metal tubes 11 each have one end disposed within the mouthpiece 10 and terminating flush with the face of the mouthpiece. The tubes 11 simply constitute air passages and the other ends of the tubes carry sounding tubes 12. The tubes 12 are closed at both ends and are preferably 60 formed of a pair of tube sections fitted into sleeves 13 integral with, or fixed to the tubes 11.

Inasmuch as the combined diameters of the tubes is considerably greater than the 70 length of the mouthpiece 10 I arrange the tubes 12 in generally semi-circular or arcuate formation about the mouthpiece, the tubes 11 being properly bent to dispose the tubes 12 in lateral juxtaposition and in a 75 general curved line, as best seen in Fig. 1.

Certain of the tubes 12 sound when air is drawn inwardly through their associated tubes 11, and others of the tubes 12 sound when air is blown outwardly through their 80 tubes 11. One of the inhaling tubes is indicated in section in Fig. 2, and one of the exhaling tubes is shown in section in Fig. 3.

Referring first to Fig. 2, it will be noted that the particular inhaling tube shown consists of the two tube section 12^a and 12^b, the open ends of which face each other and are embraced by the sleeve 13. The tube 11 enters the sleeve 13 between the ends of the two tube sections 12^a and 12^b. At the opposite side of the sleeve 13 there is an intake funnel 14 with its enlarged end outermost, so that the draft of air entering through the funnel will be in the nature of a fine jet 90 striking the edge of a dividing plate 15 carried by one of the tube sections 12^a, 12^b. 95

As shown in Fig. 2, and also in Fig. 4, the dividing plate 15 is in the nature of a rigid bridge extending partially across the bottom of section 12^a. The air jet entering through 100 the funnel 14 is divided by the member 15, part of the air stream being directed into the tube section 12^a, and part being directed into the tube section 12^b. The air stream thus sets up vibrations in the two columns 105 of air in the two tube sections, and the component of these vibrations produces a musical note which is audible at the funnel 14.

One of the exhaling pipes is shown in Fig. 3, wherein it will be noted that the end of the pipe 11 is reduced at 11^a and enters the sleeve 13 between the two sections 12^a and

12^d of one of the exhaling tubes 12. The air jet entering between the two sections of the tube is divided by a plate 17 and escapes through an outlet opening 18 arranged in 5 the sleeve 13 opposite the tube 11.

Here again, the air stream in its passage from the tube 11 to the outlet 18 will set up vibrations in the columns of air contained in both of the tubes, and the component of 10 these vibrations will be a tonal sound audible through the outlet 18.

From the foregoing description it will be apparent that the particular tones produced by the series of closed tubes are subject to a 15 wide range of variations, depending upon the relative lengths of the tube sections, as well as the combined lengths thereof. In order that the device may be readily played by one unfamiliar with it, I preferably use 20 the same notes which are used on a harmonica, and anyone who plays a harmonica will understand how to play the instrument of the present invention.

In order to amplify the tones, I enclose 25 the funnels 14 and the outlet members 18 in amplifying horns 20. These horns are secured in any appropriate manner to the sleeves 13, and their closed upper ends are arranged closely adjacent the funnel 14 or 30 outlet 18 as the case may be. The horns are of gradually increasing width toward their open lower ends, so that the tones emitted from the various tubes 12 will be amplified.

Obviously, various changes and alterations 35 might be made in the general form and arrangement of parts described without departing from the invention. Hence I do not wish to limit myself to the details set forth, but shall consider myself at liberty to make 40 such changes and alterations as fairly fall within the spirit and scope of the appended claims.

I claim:

1. In a musical instrument, a sounding tube 45 closed at both ends and having a lateral air inlet and outlet in its intermediate portion, a transverse divider plate arranged in the tube adjacent the inlet for splitting the stream of incoming air to direct part of said stream toward both ends of the tube, said tube including a pair of open ended opposed tube sections and a sleeve receiving the open ends of the sections.

2. In a musical instrument, a sounding tube 55 closed at both ends and having a lateral air inlet and outlet in its intermediate portion, a transverse divider plate arranged in the tube adjacent the inlet for splitting the stream toward both ends of the tube, said divider plate constituting a transverse partition extending more than half the width of the tube, said sleeve having the air inlet and air outlet openings therein.

3. A musical instrument including a 65 mouthpiece, a series of sounding tubes closed

at both ends, pipes constituting air passageways connecting the intermediate portions of all of said tubes to the mouthpiece, the mouthpiece ends of said pipes being arranged in lateral juxtaposition. 70

4. A musical instrument including a mouthpiece, a series of sounding tubes closed at both ends, pipes constituting air passageways connecting the intermediate portions of all of said tubes to the mouthpiece, the mouthpiece ends of said pipes being arranged in lateral juxtaposition, the tubes being arranged in a curved series and spaced from the mouthpiece by the pipes. 75

5. A musical instrument including a 80 mouthpiece, a series of sounding tubes closed at both ends, pipes constituting air passageways connecting the intermediate portions of all of said tubes to the mouthpiece, the mouthpiece ends of said pipes being arranged in lateral juxtaposition, openings in the tubes arranged at the opposite sides from the pipe openings. 85

6. A musical instrument including a 90 mouthpiece, a series of sounding tubes closed at both ends, pipes constituting air passageways connecting the intermediate portions of all of said tube to the mouthpiece, the mouthpiece ends of said pipes being arranged in lateral juxtaposition, openings in 95 the tubes arranged at the opposite sides from the pipe openings, one opening in each tube constituting an air inlet opening, the other opening in each tube constituting an air outlet opening, and non-vibratory transverse divider plates in the tubes for splitting the air streams entering through the inlet openings, certain of the tubes sounding as air is drawn inwardly through the pipes, the other tubes sounding as air is blown outwardly through 100 the pipes. 105

7. A musical instrument including a mouthpiece, a series of sounding tubes closed at both ends, pipes constituting air passageways connecting the intermediate portions of all of said tubes to the mouthpiece, the mouthpiece ends of said pipes being arranged in lateral juxtaposition, openings in the tubes arranged at the opposite sides from the pipe openings, one opening in each tube constituting an air inlet opening, the other opening in each tube constituting an air outlet opening, and non-vibratory transverse divider plates in the tubes for splitting the air streams entering through the inlet openings, certain of the tubes sounding as air is drawn inwardly through the pipes, the other tubes sounding as air is blown outwardly through the pipes, said tubes each comprising pairs of open ended tube sections facing 110 each other, and sleeves carried by the pipes receiving the open ends of the sections. 115

8. A musical instrument including a mouthpiece, a series of sounding tubes closed at both ends, pipes constituting air passage- 120

130

- ways connecting the intermediate portions of all of said tubes to the mouthpiece, the mouthpiece ends of said pipes being arranged in lateral juxtaposition, openings in 5 the tubes arranged at the opposite sides from the pipe openings, one opening in each tube constituting an air inlet opening, the other opening in each tube constituting an air outlet opening, and non-vibratory transverse 10 divider plates in the tubes for splitting the air streams entering through the inlet openings, certain of the tubes sounding as air is drawn inwardly through the pipes, the other tubes sounding as air is blown outwardly 15 through the pipes, said tubes each comprising pairs of open ended tube sections facing each other, and sleeves carried by the pipes receiving the open ends of the sections, the divider plates being formed as transverse 20 partitions partially closing the open end of one tube of each section.
9. A musical instrument including a mouthpiece, a series of sounding tubes closed at both ends, pipes constituting air passage- 25 ways connecting the intermediate portions of all of said tubes to the mouthpiece, the mouthpiece ends of said pipes being arranged in lateral juxtaposition, openings in the tubes arranged at the opposite sides from the pipe openings, one opening in each tube 30 constituting an air inlet opening, the other opening in each tube constituting an air outlet opening, non-vibratory transverse divider plates in the tubes for splitting the air streams entering through the inlet openings, certain of the tubes sounding as air is drawn inwardly through the pipes, the other tubes sounding as air is blown outwardly through the pipes, said tubes each comprising pairs of open ended tube sections facing each 35 other, sleeves carried by the pipes receiving the open ends of the sections, and amplifiers carried by the sleeves, each closed at one end and flaring at its other end.
11. A device as set forth in claim 6, and 40 wherein the inlet opening of each tube is restricted to cause an air jet to strike the edge of the divider plate.
12. A device as set forth in claim 6, and 45 wherein the mouthpiece is in the nature of an elongated bar receiving the pipe ends and the sounding tubes are supported by the pipes in a curved line spaced from the bar.

WALTER HANSELL.
